J. W. PRICE

AIR CHUCK

Filed Nov. 16, 1922

UNITED STATES PATENT OFFICE.

JAMES W. PRICE, OF TULSA, OKLAHOMA, ASSIGNOR TO TULSA INVENTION COMPANY, OF TULSA, OKLAHOMA, A CORPORATION.

AIR CHUCK.

Application filed November 16, 1922. Serial No. 601,377.

To all whom it may concern:

Be it known that I, JAMES W. PRICE, a citizen of the United States, and a resident of Tulsa, in the county of Tulsa and State 5 of Oklahoma, have invented certain new and useful Improvements in Air Chucks, of which the following is a specification.

My invention relates to improvements in air valves, commonly known as air chucks, 10 and consists of the constructions, combinations, and mode of operation herein described and claimed.

An object of the invention is to provide an air chuck which can be set for any desired pressure of air with which it is desired to fill a tire, a suitable indication being given to the operator when such pressure is reached so that he may be warned to remove the chuck.

20 A further object of the invention is to provide an air chuck which has a thumb piece 25 slideable beside a scale of pressures and having an arrangement for varying a certain leverage, the leverage being overcome when the pressure of air in the tire corresponds with the indication in the scale at which the thumb piece is set.

Other objects and advantages will appear 30 in the following specification, reference being had to the accompanying drawing, in which:

Fig. 1 is a perspective view illustrating the general aspect of the improved air chuck,

35 Fig. 2 is a longitudinal section,

Fig. 3 is a plan view,

Fig. 4 is a detail cross section on the line 4-4 of Fig. 2,

40 Fig. 5 is a detail enlarged section of parts of the valve mechanism at the left of Fig. 2,

Fig. 6 is a detail perspective view of the lever piston,

Fig. 7 is a detail perspective view of the valve piston,

45 Fig. 8 is a detail perspective view of the thumb piece, and

Fig. 9 is a detail perspective view of the slider which corresponds to the weight arm of a lever.

50 Every motorist is familiar with the valve devices on the ends of the length of hose in front of gasoline filling stations which furnish compressed air for the inflation of automobile tires free of charge. These valve de-

vices have become known as air chucks, and 55 the invention, relating to such, is so termed in the following description and claims.

The construction comprises a body 1 which has an upstanding wall 2 (Fig. 2) defining a chamber 3 in which a lever 4 is 60 located. The chamber 3 is closed by a lid 5, but this lid has a narrow longitudinal slot 6 and a wider communicating slot 7. The lid is fastened on the body by any suitable securing means, screws 8 being shown 65 merely as an illustration of such means.

A thumb piece 9 occupies the larger slot 7. It has a shank 10 which extends through the slot 6 into the chamber 3. Here it has connection with a slider 11 which, in turn, has a spring extension 12, rounded at 13, to slidably bear on the lever 4. The shank 10 of the thumb piece has a portion cut out at 14 (Fig. 8) so as to define two legs which are inserted in corresponding openings in the slider and then upset, very much the same as an ordinary rivet would be upset.

70 There is a purpose, other than providing the two legs, in cutting the shank 10 at 14. The upper wall of this cut out place furnishes a foundation, as it were, to rest upon the upper side of the slider and keep the thumb piece in proper relation to the slider. Were it not for this foundation, there is a 75 possibility of the shank 10 becoming loose and working through the slider, and in any event, causing an annoyance which the simple remedy illustrated easily avoids.

80 The slider 11 is a little wider than the spring extension 12 (Fig. 4). The slider occupies grooves 15 in the sides of the chamber 3, or rather in the sides of the wall 2 near the top. The grooves 15 furnish guides for the slide, and thus relieve the thumb piece 9 of any tendency to bind in the slot 7. It is desirable that the thumb piece 9 and spring extension 12 be capable of free 85 movement.

90 There is an arrow 16, or any other suitable indicating mark, on the top surface of the thumb piece. This top surface is also suitably roughened according to a common practice. The arrow registers with the calibrations 17 of a scale engraved or otherwise impressed on the lid 5 at one side of the 100 slot 7. It is to be observed that this side is a little wider than the opposite side. The 105 obvious purpose is to provide more room

for the scale 17. There is no particular virtue in this specific arrangement because both the scale and thumb piece may be arranged otherwise without affecting the invention itself.

- A pin 18 serves as the fulcrum for the lever 4. The opposite end of this lever has a rounded head 19 which bears on a lever piston 20 in a bore 21 in the valve head 22. 10 This bore communicates with a duct 23 which leads to a passage 24 communicating with the atmosphere. The upper end of this passage terminates in an upstanding valve ring or seat 25, and the gasket 26 of a valve piston 27 rests on this seat so as to normally obstruct the passage of air from the valve chamber 28.

This chamber has communication with a bore 29 through which the compressed air 20 passes from the nipple 30 and the usual hose connection (not shown). The pressure of air is sufficient to keep the valve piston 27 seated, but in order to anticipate a possible sticking of the piston, a spring 31 is arranged to bear on top of the piston.

A screw plug 32 furnishes a seat for the upper end of the spring. This screw plug bears on a washer 33 which prevents leakage of air from the valve chamber 28. The valve piston 27 is fluted at 34 (Fig. 7) to provide peripheral air passages. The diameter of the valve piston is substantially the same as that of the chamber 28, and this keeps the piston from rattling.

35 It is to be observed that the valve seat 25 stands above the bottom of the chamber 28. Its outside diameter is not as great as the recess 35 which contains the gasket 26. The purpose of this arrangement is: repeated seating of the piston will wear and compress the gasket. If the valve seat were large enough to extend over the area of the exposed metallic part of the piston, leakage of air would result. As it is, the valve seat can press far into the gasket and never allow the air to leak past.

A stem 37 depends from the valve piston 27. This stem has a flattened or spade end 38. It looks like a cone in side elevation in 50 Fig. 2, but is in fact arranged as shown in Fig. 7. The spade end rests upon the valve tube 39 (dotted lines in Fig. 7) and a downward pressure on the air chuck will lift the valve piston 27 and let the air through 55 from the valve chamber 28.

The lower extremity of the valve head 22 is recessed at 40 to receive a rubber washer 41. This rubber washer is intended to press on the end of the valve tube 39 and prevent 60 air from escaping in a filling operation. The orifice 42 in the center of the washer is purposely made smaller than the passage 24 so as to guard against the escape of air, in filling, should the air chuck be placed slightly 65 off center on the valve tube 39. A metal

washer 43 holds the washer 41 in place. This in turn is secured by screws (not shown) or other suitable means.

At one side of the bore 21 there is an orifice 44 at which the air escapes with a hissing sound when the pressure of air in the tire equals the adjusted leverage and the lever piston 20 is raised in the bore as a result of the pressure equalization. The hissing sound would ordinarily constitute a sufficient warning for the operator to remove the air chuck, but in order to make such warning plainer, a reed 45 (Fig. 5) is fitted in the orifice 44 in any suitable way as to cause the escaping air to vibrate it.

Certain minor details of construction consist of making the central hole in the gasket 26 sufficiently larger than the stem 37 to readily enable pulling the gasket over the spade end 38. Another detail consists in making the lid 5 with a depending flange at the left end to close the left end of the chamber 3. This flange forms the other wall of the chamber. The slots 6 and 7 are shown as falling short of the left end of the lid because it is not necessary that they extend full length unless the scale 17 be made longer to include greater pressures.

The operation may be readily understood with the above construction in mind. The operator grasps the air chuck in one hand and slides the thumb piece 9 along the scale 17 until the arrow 16 points to the pressure at which he wishes the air to be in the tire.

Sliding the thumb piece 9 along the slot 7 moves the slider 11 in the grooves 15 and also the rounded end 13 of the extension 12 over the lever 4. The extension 12, although designated as a spring extension, is in practice rigid enough to fully perform the function of a weight arm in a lever of the particular type represented in Fig. 2.

The reader can see at once that the farther the end 13 is moved away from the fulcrum 18, the greater will be the pressure or force required on the free end 19 of the lever to rock it upon the fulcrum. For example, if the arrow 16 be moved to the calibration "80", a greater force will be required at the end 19 to rock the lever than if it were moved to the calibration "60".

But assume that the operator has moved the thumb piece so that the arrow registers with the calibration "80". He now sets the valve head 22 over the valve stem 39 and presses down. The engagement of the spade end 38 unseats the valve piston 27 so that air flows into the tire. The operator must press down sufficiently hard to bring the washer 41 into contact with the rim of the valve stem 39 and thus prevent the escape of air.

Air will continue to flow into the tire until the pressure beneath the lever piston 20 and rounded end 19 (force arm) equals

and slightly exceeds the pressure represented by the position of the point 13 (weight arm) of the slider 11. Immediately, upon reaching this condition, the piston 20 will 5 rise until the orifice 44 is uncovered, whereupon the operator will be warned by the hissing sound of the escaping air.

Besides issuing a warning, the orifice 44 has the function of a safety device. Inasmuch as it permits the escape of excess air, it presents over-inflation of the tire and a possible bursting thereof in the event of any inattention from the operator.

While the construction and arrangement 15 of the improved air chuck as herein described and claimed, is that of a generally preferred form, obviously modifications and changes may be made without departing from the spirit of the invention or the scope 20 of the claims.

I claim:—

1. An air chuck of the character described comprising a chambered body having guide grooves, and a communicating bore, said bore merging with an air pressure duct and having an orifice, a lever situated in the chamber, a slide which is movable in the grooves, a lid having communicating slots of which one is occupied by a thumb piece 30 and the other by a shank which extends into connection with the slide, means associated with both the lid and thumb piece by which the slide can be set to various positions in respect to the lever, and a piston situated 35 in said communicating bore covering said orifice and bearing on the lever to overcome the pressure of the slide when the air pressure in the duct approximates the pressure at which it is set, said piston then uncovering said orifice.

2. An air chuck comprising a body having an upstanding wall defining a chamber, a head having a bore communicating with the chamber and having a relief orifice leading 45 from the bore, a piston in the bore cov-

ering the orifice, a lever pivoted in the chamber engaging one end of the piston, a lid mounted upon said wall to complete the chamber, said lid having a pair of slots, a thumb piece slideable in one slot and having 50 a shank extending through the other into the chamber, and means carried by the shank slideable along the lever to vary the pressure upon said piston.

3. An air chuck comprising a body having 55 an upstanding wall defining a chamber, a head having a bore communicating with the chamber and having a relief orifice leading from the bore, a piston in the bore covering the orifice, a lever pivoted in the chamber engaging one end of the piston, a lid mounted upon said wall to complete the chamber, said lid having a pair of slots, a thumb piece slideable in one slot, a shank 60 carried by the thumb piece extending 65 through the other slot into the chamber and having a cut out portion providing legs and a foundation, and means slideable along the lever to vary the pressure on the piston including a portion held against said foundation by said legs.

4. An air chuck comprising a body having 70 an upstanding wall with opposing internal grooves, a head having a bore and a relief orifice, a piston in the bore closing 75 the orifice, a lid applied to the wall to define a chamber with which said bore communicates, said lid having a narrow and a wide slot, a lever pivoted in the chamber having a head bearing on one end of the 80 piston, a thumb piece slideable in the wide slot, a shank carried thereby extending through the narrow slot into the chamber, a spring 85 engaging the lever, and a slider, of which said spring is a part, occupying said grooves said shank having a cut-out portion providing legs to receive the slider and a foundation against which said slider is held by the legs.

JAMES W. PRICE.
